UNITED STATES PATENT OFFICE.

FRED STINES, OF NEWTON, IOWA.

SAW-GUARD.

1,374,331.

Specification of Letters Patent. Patented Apr. 12, 1921.

Application filed March 18, 1919. Serial No. 283,409.

To all whom it may concern:

Be it known that I, FRED STINES, a citizen of the United States, and a resident of Newton, in the county of Jasper and State 5 of Iowa, have invented a certain new and useful Saw-Guard, of which the following is a specification.

The object of my invention is to provide a saw guard of simple, durable and inexpensive construction.

More particularly it is my object to provide a saw guard having a vertically slideable member so constructed as to be capable of being swung laterally away from the 15 saw, which vertically slideable member has saw guard members pivoted at its lower end.

Still a further object is to provide on one side of said last saw guard members a means for preventing the stock from kicking back.

With these and other objects in view 20 my invention consists in the construction, arrangement and combination of the various parts of the device, whereby the objects contemplated are attained, as hereinafter more 25 fully set forth, pointed out in my claim and illustrated in the accompanying drawings, in which:

Figure 1 shows a side elevation of a saw 30 guard embodying my invention.

Fig. 2 shows a front elevation of the same.

Fig. 3 shows a vertical, sectional view taken on the line 3—3 of Fig. 2.

Fig. 4 shows a transverse, vertical, sectional view taken on the line 4—4 of Fig. 3.

Fig. 5 shows a horizontal, sectional view 35 taken on the line 5—5 of Fig. 1; and

Fig. 6 shows a detail view of part of the device.

In the accompanying drawings I have 40 used the reference numeral 10 to indicate generally a saw table. The saw 11 is mounted for rotation below the table and projects upwardly through a slot in the table in the ordinary way.

Above the table is shown a support 12 on 45 which is a downwardly extending supporting member 13 preferably of tubular form.

Braces 15, 16 and 17 are provided for the supporting member 13.

It will be noticed that the braces are 50 inclined away from the member 13 in such a way as not to interfere with the operation of the parts as hereinafter described.

Rotatably mounted on the lower end of the 55 supporting member 13 is an ordinary T-

fitting 18 which receives and is fixed to a bushing 19.

The bushing 19 projects below the fitting 18 and is provided in its lower surface with opposite slots 20.

Extended through the lower end of the supporting member 13 is a pin 21. In one position of the rotation of the T-fitting the pin 21 is received in the slot 20.

Extending laterally from the T-fitting 18 65 is a piece of pipe 22 on the outer end of which is another T-fitting 23 in which the upright pipe 24 is slidably but non-rotatably mounted.

The pipe 24 is provided with a slot 25 70 and a key 27 is extended through the wall of the T-fitting 23 and into the slot 25, as illustrated in Fig. 5.

Between the upright pipe 24 and the T-fitting 23 is a bushing 28 which has a slot 75 registering with the slot 25 through which the key 27 extends, as shown in Fig. 5.

The set screw 29 extends through the wall of the T-fitting 23 and the bushing 28 and is designed to lock the upright pipe 24 in various 80 positions of its vertical adjustment.

Mounted in the lower end of the pipe 24 is a short shaft 30 having at its lower end a downwardly opening U-shaped yoke 31, clearly shown in Figs. 3 and 4.

Pivoted between the arms of the yoke 31 85 are two saw guard members extending in opposite directions from the yoke 31 and comprising downwardly opening channels 32 and 33.

The saw guard member 32 is provided 90 with a pair of ears 34 which extend to position between the arms of the yoke 31 and are pivoted on a bolt 35 mounted in said arms.

On the saw guard member 33 is a bearing 95 36 received between the ears 34 and pivotally mounted on a bolt 35.

At the lower portion of the arms of the yoke 31 are inwardly extending lugs 37 100 which limit the downward swinging movement of the saw guard members 32 and 33. The walls of the channels of the saw guard members 32 and 33 are provided with notches 38 to receive said lugs, as illustrated 105 in Fig. 3.

At the outer end of the saw guard member 32 is an upwardly and outwardly extending arm 40.

At the outer end of the saw guard member 110

33 is a smooth flat surface on which is mounted a plate 41 having a toothed lower edge 42. The plate 41 has elongated slots 43 through which are extended screws 44 mounted in the saw guard member 33. By the construction just shown the plate 41 may be adjusted.

In the practical operation of my improved saw guard, the parts are assembled and 10 moved to the position shown in Figs. 1 and 2.

The upright pipe 24 is then vertically adjusted and locked by means of the set screw 29 at such a height as to permit the work, such as that indicated at 45 by dotted lines 15 in Fig. 1, to be readily shoved under the saw guard members 32 and 33.

The pins 21 and slots 20 and the slot 25 are so located as to hold the saw guard members 33 and 32 in proper position above the 20 saw, as illustrated in Figs. 1 and 2.

The work is then shoved in under the arm 40, which is so inclined as to permit the work to raise the saw guard member 32 readily.

25 As the work is moved along the table 10 and is sawed, it will raise the saw guard member 33 so that the saw guard members 32 and 33 will rest on top of the work, as illustrated by dotted lines in Fig. 1.

30 It will thus be seen that the saw guard does not interfere in any way with the manipulation of the work or material being operated on, and some considerable variation in the thickness of material may be had without readjusting the pipe 24 vertically.

35 On account of the pivotal mounting of the members 32 and 33 they adjust themselves to materials of different thicknesses which are being sawed.

40 On account of the channel-shaped form of the saw guard members, the sawdust and splinters which may be thrown from the wood being sawed cannot be thrown up so as to strike the workman.

45 Furthermore if a piece should be broken out of the saw it cannot be thrown so as to strike the workman.

One accident that occurs with undesirable frequency in a planing mill or other place 50 where wood is sawed, arises from the fact that the saw will sometimes strike a knot in the wood or the wood will bind on the saw tending to cause the wood to rise up with

the teeth of the saw and then ride along the points of the teeth causing it to be thrown 55 from the saw with considerable force. This throwing of the wood is called a "kick back" and is prevented with my saw guard by the downwardly inclined arm 33 having the plate 41 with serrations 42 at its end. 60

It will be noted that when desired the upright 24 may be raised until the notches 20 are clear of the pins 21 and swung around on the supporting member 13 to position shown by dotted lines in Fig. 2 where it will 65 be readily out of the way.

It will be noted also that the upright 24 is supported on the member 13 outside of the vertical plane in which the saw rests.

This is desirable for the reason that sometimes a long piece of wood is sawed at the end and the wood will extend upwardly a considerable distance, and it is desired that the guard mechanism be out of the way when the wood is sawed in the manner just described.

70 My guard is of very simple and inexpensive construction and has numerous advantages including those mentioned above.

Some changes may be made in the construction and arrangement of the various parts of my improved device without departing from the essential spirit of my invention, and it is my intention to cover by 80 my claim any modified forms of structure or 85 use of mechanical equivalents which may be included within their scope.

I claim as my invention:

In a saw guard structure, an upright member having formed at the lower end 90 thereof a downwardly opening U-shaped yoke, the arms of said yoke having at their lower portions inwardly projecting lugs, saw guard members comprising downwardly opening channel-shaped members, each provided at its upper portion with a bearing received between the arms of said yoke and projecting away from the body of the saw guard member, a common bolt extended 95 through said arms, and through said bearings, the walls of said channel-shaped saw guard members, having notches to receive said lugs.

Des Moines, Iowa, February 7, 1919.

FRED STINES.
